UNITED STATES PATENT OFFICE.

ALFRED MARKS, OF BROOKLYN, NEW YORK.

CLOSURE FASTENER.

Application filed June 11, 1924. Serial No. 719,386.

To all whom it may concern:

Be it known that I, ALFRED MARKS, a citizen of the United States, residing at Brooklyn, in the county of Kings and State 5 of New York, have invented certain new and useful Improvements in a Closure Fastener, of which the following is a specification.

This invention relates to new and useful 10 improvements in closure fasteners and has for its principal object to provide a simple and efficient device which is adapted to be associated with a sliding closure such as a door or a window for normally holding 15 the same in a closed position.

A further object of the invention is to provide a closure fastener of the above mentioned character, which is automatic in its operation and will enable the closure to be 20 readily opened without any difficulty.

A still further object of the invention is to provide a closure fastener of the above mentioned character, which is simple in construction, inexpensive, strong and durable 25 and furthermore adapted for the purposes for which it is designated.

Other objects and advantages of this invention will become apparent during the course of the following description.

30 In the accompanying drawing forming a part of this specification and in which like numerals designate like parts throughout the same:

Figure 1 is a fragmentary front elevation of a closure for a receptacle showing my fastener associated therewith.

Figure 2 is a sectional view taken approximately on line 2—2 of Figure 1.

Figure 3 is a detail perspective view of 40 a portion of the closure showing the opening provided therein for receiving the fastener, and

Figure 4 is a fragmentary sectional view of a window with my invention associated 45 therewith.

In the drawing wherein for the purpose of illustration is shown the preferred embodiment of my invention, the numeral 1 designates a receptacle of any well known construction, the same being provided with a curved top 2, the same being provided with an opening 3 whereby access to the receptacle may be had. A closure 4 for the opening 3 is adapted for slidable movement between the guide strips 5 and 6 respectively which are secured to the curved top 2 ad-

jacent the ends of the receptacle in the manner clearly illustrated at 7 in Figure 1 of the drawing.

The forward portion of the closure 4 is 60 provided with suitable handles 8 for facilitating the sliding movement thereof to uncover or close the opening as the case may be and arranged in the forward portion of the cover or closure 4 adjacent the ends 65 thereof are the openings such as are illustrated at 9 in the drawing. This is more clearly illustrated in Figure 3. The purpose of the opening 9 in the forward lower portion of the closure will hereinafter be 70 more fully described.

Each of the guide strips is provided with an opening 10 in the forward end thereof and adapted to be seated in said opening of each strip is the spherical member 11. Each 75 of these spherical members extends through each of the openings provided in the strip and is adapted for engagement with the openings 9 provided in the forward lower portions of the closure 4. For the purpose 80 of normally holding the spherical member in engagement with the openings 9 whereby a fastener for the closure is provided, I provide each strip with a pair of bolts 12 and 13 which extend laterally from the strip on 85 opposite sides of the opening 11 and a flat spring member 14 is adapted for slidable movement on the bolt and engages the outer portion of the spherical member 11 to hold the same in engagement with the openings 90 9 in the closure 4.

Normally the parts are arranged as shown in Figure 2 of the drawing and the springs 14 urge the spherical members 11 into engagement with the openings 9 whereby a 95 fastener for the closure 4 is provided. When the closure 4 is moved to an open position, the spherical members 11 will move outwardly out of engagement with the openings 9 and force the flat springs outwardly and simultaneously placing the same under tension. When the closure 4 is returned to its normal position, the spherical member 11 will again seat in the openings 9 and hold the closure in a closed position.

In Figure 4 of the drawing the invention is shown as associated with the sliding window 15 and the guide rails 16 therefor. The window sash is provided with a metal plate 17 in which an opening or recess 18 is provided for the reception of the spherical member 19, the latter extending through a 100 105 110

suitable opening 20 provided in the guide rail or strip 16 and a flat spring 21 operates on the bolts 22 and 23 respectively for normally holding the spherical member in engagement with the recess 18 provided in the plate 17. In this manner, the window will be held in a closed position.

It will thus be seen from the foregoing description, that a closure fastener has been provided which will be automatic in its operation and at all times positive in its action. The simplicity of my device enables the same to be readily and easily placed in position for use and will be strong and durable as well as inexpensive.

While I have shown the preferred embodiment of my invention, it is to be understood that various changes in the size, shape and arrangement of parts may be resorted to without departing from the spirit of the

invention and the scope of the appended claim.

Having thus described the invention, what I claim is:—

In combination, a movable member, a stationary member, both of said members provided with openings registrable with each other, a sphere in one of the said openings for engaging the other opening so as to hold the movable member locked in relation to the stationary member, a pair of bolts on the member having the sphere in its opening, one on each side of the opening, and a flat spring held by one of said bolts and slidable on the other of said bolts and provided intermediate its ends with a pocket for receiving the sphere.

In testimony whereof I affix my signature.

ALFRED MARKS.
